CUTTING BLOCK

Joseph Janes, Somerville, Mass.

Application November 9, 1938, Serial No. 239,671

4 Claims. (Cl. 146—215)

The invention relates to a cutting block of the type used by butchers on which to cut meat.

Among the objects of the invention are:

To provide a reversible block having two cutting surfaces;

To so support the block that it can easily be removed from its support, either for purpose of reversal or for purpose of resurfacing its cutting surfaces, and as easily be returned to its support after such removal;

To provide a construction which permits of the cutting surfaces of the block being repeatedly resurfaced; and

To provide a stable and attractive support for the block, and especially one that can readily be kept clean.

The invention can best be seen and understood by reference to the drawings, in which

Fig. 1 is a perspective of a cutting block embodying the invention, with an element or side of its supporting bed removed, and with the legs of the supporting bed cut away in part.

Fig. 2 shows in perspective the element or side removed from the supporting bed as shown in Fig. 1.

Fig. 3 is a section on the line 3—3 of Fig. 1.

Fig. 4 is a cross section of a detail of construction to which special reference will later be made; and

Fig. 5 is a front elevation of the cutting block with the element or side shown in Fig. 2 removed, and with the legs which support the bed cut away in part.

Referring to the drawings:

1 represents the block having cutting faces 2 and 3, respectively. The block is composed of a plurality of sections 4 glued together, and otherwise bound together by tie rods 5 having threaded ends 6 upon which are arranged nuts 7 and washers 8. The block is made of some considerable thickness as the purpose is to provide a block that can be reversed in its support so that cuttings may be made from off both of its cutting faces before removal of the block from its support for the purpose of resurfacing these faces, and, also, a block admitting of repeated resurfacing of its cutting faces. Along the middle of the block, about midway between its two cutting faces, it is provided with a continuous channel 9 extending around all of its four sides. 10 represents the bottom of this channel, 11 its top edge, and 12 its bottom edge.

The block is socketed in a supporting bed 14. This bed is made of metal and consists of a bottom 15 and sides 16, 17, 18 and 19. The bottom

and sides co-operate to form a socket or chamber 20 within which substantially one-half portion of the block is contained, the sides of the bed embracing the contained portion of the block. The bottom 15 of the supporting bed and three 5 of its sides, or the sides 16, 17 and 18 as shown, are preferably integrally connected being cast in one piece. One side, or the side 19 of the bed, is removable and is secured to the bottom 15 of the bed and to the fixed sides 17 and 18 of the bed 10 adjacent to it. The removable side 19 secured to the bottom 15 of the bed in part by means of pins 22 on lugs 23 inwardly projecting from the removable side adjacent the bottom thereof, and these pins fit within pin sockets 24 in the bottom 15 of the bed (see Fig. 4). The attachment is further secured by screws 25 which are passed through the removable side and fastened into lugs 26 on the ends of the adjacent fixed sides 16 and 18, respectively, of the bed. 20

All the sides of the bed along their top edge portions 27 are turned inwardly to enter the channel 9 cut in the block, the block then resting on the tops of these inturned sides by the top edge 11 of the channel in the block resting upon the 25 top edge 28 of the inturned portion of the respective sides. The edge 28 is a finished edge in order that the block along the top of its channel where it engages this edge shall make tight and finished engagement therewith. The depth of 30 the bed is such that when the block becomes thus supported the cutting face on the contained socketed portion of the block will lie clear of the bottom of the bed. It will, also, be noted that the block can become thus socketed only after the 35 removal of its removable side 19. After the removal of this side the block is slid into place and the removable side is then applied and fastened when it will co-operate in the support of the block as does the fixed sides of the bed. 40

The tie rods 5 are availed of for holding the block in place against lateral displacement within the bed in which it is socketed in order that the edges 11, along which the block is resting on the top edges 28 of the respective sides, shall 45 properly co-ordinate therewith. The tie rods are so disposed in the block that the threaded ends 6 thereof, on which are arranged the nuts 7 and washers 8, will be contained in the channel 10, the threaded ends of the rods extending through 50 and beyond the nuts. With the rods thus disposed the threaded ends of the rods will lie immediately adjacent to the turned ends 27 of the fixed sides 16, 18 of the bed. These sides are built out or thickened by bosses 30 at points 55

adjacent the threaded ends of the tie rods. Sockets 31 are formed within these bosses, and turning within these sockets are hollow nuts 32 threaded to engage the ends of the tie rods. The 5 nuts 32 are provided with heads 33 widened to engage shoulders 34 formed in the bosses when the nuts are tightened. The heads of the nuts are provided with slots 35 by which the nuts may be turned. The tightening of the nuts 32 will 10 anchor the block to the bed.

10 The bed 14 is mounted upon extensible legs 38, the bodies of which, formed of sheet metal by casting, or otherwise, are provided at their tops with flanges 39, secured by bolts 40 to the bottom 15 15 of the bed. Each of the legs contains an extensible shank 41 bearing upon its bottom end a foot 42 and this shank is secured in any adjusted position within the leg, for lengthening or shortening it, by means of a set screw 43.

20 An easy removal of the block is obtainable either for purpose of reversing it in its bed, or for purpose of refinishing its cutting faces, by first loosening the nuts 32 which connect with the tie rods. Then after removing the removable 25 side 19 of the bed the block may be drawn from the bed, sliding out upon the top edges 31 of its fixed opposing sides 17, 18. The application of the block to the bed is obtained simply by a reversal of this operation.

30 Inasmuch as the block is supported at its center repeated resurfacing of its cutting faces may be had without the necessity of obtaining a new block. As the normal height of the block diminishes by reason of resurfacing this may be 35 compensated for by lifting the bed through lengthening its supporting legs.

30 The exposed surface of the block and its bed support are capable of easy surface cleaning, and no crevices or openings are left into which solids 40 or liquids can enter and develop unsanitary conditions.

I claim:

45 1. A cutting block having a cutting face and with channels formed therein on opposite sides thereof at points removed from said cutting face, said channels presenting, respectively, bearing edges off which said block may be supported, a supporting bed within which said block is socketed having fixed sides and a detachable side, certain of said fixed sides adjoining the 50 channelled sides of said block being formed to enter and close said channels and have engagement with said bearing edges of the block whereby the block may be slidable on said sides of the bed entering said channels as aforesaid 55 into and out of socketed position in said bed

after removal of said removable side and rest upon said sides when socketed, and means for attaching said removable side to said bed.

2. A cutting block having a cutting face and with channels formed therein on all sides thereof at points removed from said cutting face, said channels presenting, respectively, bearing edges off which said block may be supported, a supporting bed within which said block is socketed having fixed sides and a detachable side, all sides 10 of said block being formed to enter and close the channels in the block to which the sides are adjacent and have engagement with said bearing edges of the block whereby the block may rest thereon when socketed and slide in and out of its socketed position on certain of said sides after removal of said removable side, and means for attaching said removable side to said bed whereby it may assist in the support of said block.

20 3. A cutting block having a cutting face and with channels formed therein on opposite sides thereof at points removed from said cutting face, said channels presenting, respectively, bearing edges off which said block may be supported, a supporting bed within which said block is socketed having fixed sides and a detachable side, said fixed sides adjoining channel sides of the block being formed to enter the channels therein and have engagement with said bearing edges of the block whereby the block may rest thereon when socketed, means for anchoring said block to the fixed sides of the bed when the block is socketed therein as aforesaid, and means for attaching said removable side to said bed.

35 4. A cutting block having a cutting face and with channels formed therein on opposite sides thereof at points removed from said cutting face, said channels presenting, respectively, bearing edges off which said block may be supported, a supporting bed within which said block is socketed having fixed sides and a detachable side, said fixed sides adjoining channeled sides of the block being formed to enter the channels therein and have engagement with said bearing edges of the block whereby the block may rest thereon when socketed, tie rods passed through said block with ends contained in the channels 40 therein adjacent fixed sides of the block, and means on fixed sides of the block attachable to 45 the ends of said tie rods whereby the block will become anchored in said bed when socketed as aforesaid, and means for attaching said removable side to said bed.

JOSEPH JANES. 55
